US0D1045514S

(12) **United States Design Patent** (10) **Patent No.:** **US D1,045,514 S**
(45) **Date of Patent:** **** Oct. 8, 2024**

(54) **TUMBLER**

(71) Applicant: **SHENZHEN SITELAI TECHNOLOGY CO., LTD.**, Shenzhen (CN)

(72) Inventor: **Shaofeng Li**, Shenzhen (CN)

(73) Assignee: **SHENZHEN SITELAI TECHNOLOGY CO., LTD.**, Shenzhen (CN)

(**) Term: **15 Years**

(21) Appl. No.: **29/915,935**

(22) Filed: **Nov. 6, 2023**

(51) **LOC (14) Cl.** **07-01**

(52) **U.S. Cl.**

USPC **D7/536; D7/533**

CLAIM

The ornamental design for a tumbler, as shown and described.

DESCRIPTION

FIG. 1 is a perspective view of a tumbler showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the tumbler that form no part of the claimed design.

1 Claim, 8 Drawing Sheets
